UNITED STATES PATENT OFFICE.

MARVIN W. FREEMAN, OF BEATRICE, NEBRASKA.

IMPROVEMENT IN REAPERS AND MOWERS.

Specification forming part of Letters Patent No. 173,851, dated February 22, 1876; application filed October 29, 1875.

To all whom it may concern:

Be it known that I, MARVIN W. FREEMAN, of Beatrice, in the county of Gage and State of Nebraska, have invented a new and useful Improvement in Reapers and Mowers, of which the following is a specification:

Figure 1 is a top view of a portion of a sickle-bar to which my improvement has been applied. Fig. 2 is a cross-section of the same, taken through the line $x x$, Fig. 1.

Similar letters of reference indicate corresponding parts.

The object of this invention is to improve the construction of the sickle-bars of reapers and mowers, so as to enable them to cut better, keep sharp longer, and work easier than when constructed in the ordinary way.

The invention consists in the sickles concaved upon their inner sides, and provided with sickle-teeth, and in the combination of the stationary adjustable sickles and their bar with the vibrating sickles and their bar, and with the dividing-fingers and the cutter-bar, as hereinafter fully described.

A is the cutter-bar, to which the fingers B are attached in the usual way. C are the lower sickles, which are secured to a bar, D. The bar D is secured to the fingers B by screws or bolts, which pass through short longitudinal slots in the fingers B, and screw into screw-holes in the bar D, so that by loosening the said screws the sickles C and their bar D may be moved forward and back as may be desired. E are the upper sickles, which are attached to the bar F. The bar F is placed in the space between the bar D and the cutter-bar A, and is kept in place against the said cutter-bar A by keepers G, attached to said cutter-bar.

The sickles C E are beveled upon the outer sides of their edges, and have sickle-teeth formed upon them, as shown in Fig. 1. The adjacent sides of the sickles C E are concaved, as shown in Figs. 1 and 2, so that they may bear upon each other only at their edges, so that the wear may keep the edges sharp, and stalks and dirt cannot get between the sickles and separate them, so that their edges may

not bear properly upon each other. The sickle-bar F and sickles E are vibrated in the usual way.

I am aware that sickle-sections have been beveled on the outside of edge, and serrated on the bevel; but this leaves the edge too thick and blunt. Mine, being serrated on the outside while the bevel is on the inside, can be sharpened on a common grindstone without injuring the serrations; and my serrations, being nearer the middle of section, will wear much longer.

By using two sickles, serrated, matched, and concave, right and left oblique edges are made to work in close proximity with each other, while by making the upper sickle-section longer than the lower one, the whole weight of the former is made to bear on the heel thereof, the main bar and bevel edges of lower sections thus retaining the edges close together until worn out. Thus the whole weight of the upper sickle does not rest on the edges of the lower sickle-sections, but is distributed between the heels and points of upper sections, the heels resting on main bar, and edges on edges of lower section. I am enabled in this way to compensate for wear of sections.

By slotting the fingers I am enabled to place the under forward of the upper sickle-bar, so as to adapt the sickles to light or heavy grass. The advanced lower sickle causes, in heavy grass, its compression into a small space before it is cut, and reduces the cutting-surface of upper sections, lessening the power required fully forty per cent. Hence,

What I claim is—

1. The ledger-bar D and fingers B, connected by screws, adjustable in slots of fingers, as and for the purpose described.
2. The combination of upper cutters and lower ledger-blades, matched, oppositely concaved, and serrated on outside bevel, as and for the purpose specified.

MARVIN W. FREEMAN.
